UNITED STATES PATENT OFFICE.

LUTHER PULLIAM, OF IROTON, MISSOURI, ASSIGNOR TO WHITWORTH & SONS, OF SAME PLACE, OSWALD S. PULLIAM, OF ST. LOUIS, AND JULIA E. SWANK, OF CHARLESTON, MISSOURI.

WAGON-BOLSTER SPRING.

SPECIFICATION forming part of Letters Patent No. 394,935, dated December 18, 1888.

Application filed September 29, 1888. Serial No. 286,796. (No model.)

To all whom it may concern:

Be it known that I, LUTHER PULLIAM, of Ironton, Missouri, have made a new and useful Improvement in Wagon-Bolster Springs, 5 substantially as is hereinafter described and claimed, aided by the annexed drawings, making part of this specification, in which—

Figure 1 is a side elevation of a wagon-bolster having the improved device applied thereto; Fig. 2, an end elevation of the same; Fig. 3, a section on the line 3 3 of Fig. 2, and Fig. 4 a section on the line 4 4 of Fig. 1.

The same letters of reference denote the same parts.

15 The bolster A and standards B B are of the usual construction, saving as it may be modified or supplemented by the improvement in question.

20 C represents the wagon-bed, which also is of the ordinary form, with the exception of the appliances D used to connect the bed with the springs.

25 At each end thereof the bolster is supplied with a pair of arms, E E, whose function it is to uphold a pair of springs, from which in turn the wagon-bed is suspended. The arms rise from the bolster against and respectively upon opposite sides of the standard. At the lower end thereof the arms 30 are preferably not connected with the bolster directly in the vicinity of the standard, but at a point nearer to the center of the bolster, thereby to enable the weight of the wagon-bed to be sustained more especially by the central portion of the bolster. To this end the arm is made to consist of an upright portion, e, and a horizontal portion, e', the upright portion being made to rise from the bolster in line with the standard, and the horizontal

35 portion being extended along the side a of the bolster, and being fastened thereto at the inner end, e², of the arm. The two arms E E are conveniently attached to the bolster by means of the bolts e⁴ e⁴.

40 A saddle-shaped metallic piece, e³, is preferably placed upon the bolster at the point where the arms E E are attached, and the bolts e⁴ e⁴ pass not only through the arms E E and bolster, but also through the sides of the

piece e³, as shown. The sides may have at the 50 lower end thereof a flange, e⁵, which may aid in supporting the arms E E. The arm portions e e are, and preferably by means of the band F, tied to the standard, partly to better hold the arms in place and partly to brace 55 the standard. The band is upheld in place by reason of the tapering form of the standard. At its upper end each arm portion e is shaped substantially as shown, to enable a spring, G, to be attached thereto, substan- 60 tially as shown.

The spring hangs alongside the arm portion e, and at its lower end the spring is, by means of the appliance D, connected with the wagon-bed. The appliance D is in practice a strap 65 secured at its end d to the wagon-bed, and at its end d' made hook-shaped or of some equivalent shape to enable it to be connected with and disconnected from the spring. The straps D D for each pair of springs project from the 70 wagon-bed to come respectively against or past the arm portions e e, as shown, and they thus also serve as a means for holding the wagon-bed longitudinally from slipping. The springs are an assistance in this respect. As 75 a modification, the straps D D might be attached to a board extending across beneath and thereby supporting the wagon-bed. When it is not desired to use the springs, the wagon-bed can be detached therefrom, and 80 when it is desired to support a comparatively light load one of each pair of springs can be disconnected from the wagon-bed.

It will be noticed that no substantial obstacle is interposed between the wagon-bed and 85 the bolster beneath. The wagon-bed therefore can be hung quite low down, even when elastically supported.

I claim—

1. The combination of the bolster, the standards, the wagon-bed, the arms shaped and attached to the bolster, as described, the bands, the springs, and the straps, substantially as described.

2. The combination of the bolster, the standards, the wagon-bed, the arms, the bands, the springs, and the straps, substantially as de- 95 scribed.

3. The combination of the bolster, the standards, the wagon-bed, the arms, the springs, and the straps, substantially as described.

4. The combination of the bolster, the wagon-bed, the arms, the springs, and the straps, substantially as described.

5. The combination of the bolster, the arms E E, shaped and attached to the bolster at the central part thereof, as described, the standards, the wagon-bed, the springs, and the straps, substantially as described.

6. The combination of the bolster, the standards, the arms, and the band, substantially as described.

Witness my hand.

LUTHER PULLIAM.
